LIFTING JACK

Filed Feb. 6, 1926

Inventor:
Frank L. Gormley,
by Walter E. Lombard,
Atty.

UNITED STATES PATENT OFFICE.

FRANK L. GORMLEY, OF BROOKLINE, MASSACHUSETTS, ASSIGNOR TO THE BUDA COMPANY, OF HARVEY, ILLINOIS, A CORPORATION OF ILLINOIS.

LIFTING JACK.

Application filed February 6, 1926. Serial No. 86,418.

This invention relates to lifting jacks and particularly to locking means preventing the rotation of the ram under normal conditions, said locking means being removable from 5 the ram when it is desired to rapidly raise or lower the ram.

The object of the present invention is the provision of simple means which will obtain this desired result, which result is accomplished by the mechanism illustrated in the accompanying drawings.

For the purpose of illustrating the invention, one preferred form thereof is illustrated in the drawings, this form having 15 been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

25 Figure 1 represents an elevation of a lifting jack embodying the principles of the present invention, the upper part of which is shown in section.

Figure 2 represents a horizontal section 30 of same on line 2, 2 on Fig. 1, and

Figure 3 represents a side elevation of the upper end of said jack.

Similar characters indicate like parts throughout the several figures of the drawings.

In the drawings 10 is the base of a lifting jack having a casing 11 extending upwardly therefrom.

Within the casing 11 is a ram 12 adapted 40 to be moved vertically in the bearing 13 by means of a rotatable screw 14 having a steep pitch as shown.

The lower end of the ram 12 is provided with the usual nut in engagement with the 45 screw 14 and said screw is rotated in the usual manner through gearing by an actuating lever applied to the shaft 15.

As this mechanism forms no part of the present invention it is deemed unnecessary to 50 illustrate the same.

The ram 12 for its entire length is provided with a vertical slot 10 in its periphery into which normally projects a key 17 which when disposed in said slot 16 prevents the 55 rotation of said ram 12.

The ram 12 has a top plate 18 normally resting on the upper end of the casing 11, this plate having radial sockets 19 for the reception of any suitable tool by which the ram 12 may be moved about its axis when 60 the key 17 is removed from the slot 16.

Ordinarily, however, the ram 12 may be rotated by hand when the key 17 is removed from slot 16.

The casing 11 has an opening 20 near its 65 upper end in which said key 17 is movable toward and from the axis of the ram 12, portions of the side walls of said key being always in contact with the side walls of said opening.

On opposite sides of said opening 20 the casing 11 is provided with parallel vertical flanges 21 through which extend pins 22, 23, which pins also extend through ears formed upon a cover plate 24.

Pivottally mounted on the pin 22 is a lever 25 having an opening 26 therein through which extends the headed bolt 27, the inner end of which is threaded to said key 17.

The head 28 of said bolt is forced against 80 the outer face of lever 25 by the spring 29 interposed between the head 28 and the cover plate 24.

The lower end 30 of the lever 25 projects 85 below the lower edge of the cover plate 24 and is removed sufficiently from the casing 11 to permit the operator to grasp said lower end 30 and move the lever 25 about its pivot sufficiently to entirely disengage the key 17 from the slot 16 in ram 12.

When the jack is being operated in the usual manner a portion of the key 17 is forced into the slot 16 by means of the spring 29 and any rotation of the screw 14 will impart reciprocatory movement to the 95 ram 12.

The key 17 is always in the slot 16 when the load is being lifted, but when the load has been raised it is sometimes desirable to lower the ram quickly without using the 100 usual actuating lever as is the common practice with lifting jacks of this type.

To accomplish this the operator places his finger behind the end 30 and moves the lever 25 outwardly about its pivot, compressing 105 the spring 29 and removing the key 17 from slot 16.

The operator with one hand retains the lever 25 in this outward position thereby permitting the ram 12 to rotate freely as 110

soon as with the other hand he has given a slight turn to the ram.

As the thread of the screw 14 and its co-acting nut is of coarse pitch the ram will descend very quickly.

When it is desired to stop the ram at any point the operator simply releases the lever 25 and the expansion of spring 29 will force the key 17 into the slot 16 as soon as said slot in the rotation of the ram comes into register with said key.

This having been accomplished further rotation of the ram 12 is prevented.

Sometimes after raising the ram by the usual means it may be necessary to run out the ram a certain distance to reach the load to be lifted. In such a case the key 17 is removed from slot 16 in the manner just described and the ram is turned in a reverse direction, i. e., in a direction opposite to that in which it turns in lowering, and due to the coarse pitch of the thread of screw 14 the ram 12 may be elevated very rapidly as compared with the movement thereof when operating with the ordinary lever and the gears actuated thereby.

The locking device is all enclosed except the end 30 which is exposed in such a manner as to make it readily accessible to the operator when he desires to remove the key 17 from slot 16.

It will be noted that the return of the key into the slot 16 is automatic and requires no attention on the part of the operator.

Such a locking mechanism is a distinct improvement over jacks provided with fixed keys in the shell or casing 11 or jacks which have no provision for preventing the ram from turning during the lifting of the load.

From the foregoing explanation it is believed that the operation and many advantages of the invention will be fully understood.

Having thus described my invention, I claim:

1. In a self-lowering lifting jack provided with a steep pitch screw, a supporting casing having an elongated vertical opening therein with parallel flat sides, and a vertically movable ram in said casing freely movable downwardly on said screw when at rest and having a peripheral slot with flat parallel walls extending lengthwise thereof said slot having the same width as said opening; a flat-sided key freely movable in said casing opening in a radial path and in contact with the side walls thereof; an actuating lever pivoted at its upper end to said casing and depending from its pivot adapted to move said key outwardly from said slot; and means in the same plane with the key for automatically returning said key into said slot when said lever is released.

2. In a self-lowering lifting jack provided

with a steep pitch screw, a supporting casing having an elongated vertical opening therein with parallel flat sides, and a vertically movable ram in said casing freely movable downwardly on said screw when at rest and having a peripheral slot extending lengthwise thereof with parallel flat side walls spaced apart the same distance as the sides of said opening; a flat-sided key freely movable radially in said casing opening in contact with the side walls thereof; manually actuated means pivoted to said casing near the top of said opening for moving said key from said slot, said moving means depending from its pivot; and means for automatically returning said key into said slot when said moving means is released.

3. In a self-lowering lifting jack provided with a steep pitch screw, a supporting casing having an elongated vertical opening therein with parallel flat sides, and a vertically movable ram in said casing freely movable downwardly on said screw when at rest and having a peripheral slot extending lengthwise thereof; a flat-sided key freely movable in said casing opening in contact with the flat sides thereof; manually actuated means on said casing for moving said key radially from said slot; and resilient means and coacting directly with the key independent of said moving means for automatically returning said key into said slot as soon as said moving means is released.

4. In a self-lowering lifting jack provided with a steep pitch screw, a supporting casing having an elongated vertical opening therein with parallel flat sides, and a vertically movable ram in said casing freely movable downwardly on said screw when at rest and having a flat sided peripheral slot extending lengthwise thereof; a flat-sided key slideable in said casing opening in contact with the sides thereof and having a lateral shouldered projection radial to the axis of said ram; an actuating lever pivoted to said casing at the upper end of said opening and adapted to engage said projection to remove the key from said slot; and a spring for forcing said key into said slot when the lever is released.

5. In a self-lowering lifting jack provided with a steep pitch screw, a supporting casing, and a vertically movable ram therein having a peripheral slot extending lengthwise thereof, said ram being freely movable downwardly on said screw when the screw is at rest; a key slideable endwise in an opening in said casing; a lever pivoted to said casing and having a hole therethrough; a headed bolt extending through said hole into said key; and means for applying spring pressure to the outer end of said bolt.

6. In a self-lowering lifting jack provided with a steep pitch screw, a supporting cas-

ing having an elongated vertical opening therein with parallel flat sides, and a vertically movable ram in said casing having a peripheral slot extending lengthwise thereof, said ram being freely movable downwardly on said screw when the screw is at rest; a flat sided key slideable radially in an opening in said casing in contact with the side walls thereof and extending normally into said slot; manual means disconnected from said key but coacting with a central part thereof for removing it from said slot; and automatic means for returning the key to its normal position projecting into said slot as soon as said moving means has been released.

7. In a self-lowering lifting jack provided with a steep pitch screw, a supporting casing having an elongated vertical opening therein with flat parallel sides, and a vertically movable ram in said casing having a peripheral slot extending lengthwise thereof, said ram being freely movable downwardly on said screw when the screw is at rest; a flat sided key slideable in said opening between the side walls thereof and extending normally into said slot, said key having midway of its length a headed projection; means coacting with one side of the head of said projection for removing said key from said slot; and a spring coacting with the opposite side of the head for forcing inwardly said key and moving means.

8. In a self-lowering lifting jack provided with a steep pitch screw, a supporting casing having an elongated vertical opening therein with parallel flat sides and a vertically movable ram in said casing freely movable downwardly on said screw when at rest and having a flat sided peripheral slot extending lengthwise thereof; a flat-sided key freely movable in said opening in contact with the side walls thereof; a stud centrally disposed in said key; a spring coacting with said stud to project a portion of said key into said slot; and an actuating lever movable about a pivot at the top of said opening and depending therefrom and having a hole therein through which said stud extends, said stud having a head bearing on the outer face of said lever.

9. In a self-lowering lifting jack provided with a steep pitch screw, a supporting casing having an elongated vertical opening therein with parallel flat sides and a vertically movable ram in said casing freely movable downwardly on said screw when at rest and having a flat sided peripheral slot extending lengthwise thereof; a flat-sided key freely movable in said opening in contact with the side walls thereof; a stud centrally disposed in said key and provided with a head on its outer end; an actuating lever pivoted at its upper end with its central portion interposed between said key and head; and re-

silient means for normally forcing a portion 65 of the key into said slot.

10. In a self-lowering lifting jack provided with a steep pitch screw, a supporting casing having an elongated vertical opening therein with parallel flat sides and a vertically movable ram in said casing freely movable downwardly on said screw when at rest and having a peripheral slot extending lengthwise thereof; a flat-sided key freely movable in said opening between parallel 70 ears projecting from said casing; a closing plate secured to said ears and closing the upper and outer ends of the space between said ears; a stud centrally disposed in said key and provided with a head on its outer end; an actuating lever pivoted at its upper end to said ears and depending from said pivot with portions thereof between said key and head and its lower end extending slightly below said closing plate; and resilient means between said head and plate 75 for forcing a portion of said key into said slot when said lever is released.

11. In a self-lowering lifting jack provided with a steep pitch screw, a supporting 80 casing and a vertically movable ram in said casing freely movable lengthwise of the screw when the screw is at rest, said ram having a flat-sided vertical slot extending lengthwise of its periphery; a flat sided key 85 movable in a straight path in contact with the side walls of an opening in said casing and adapted to partially enter said slot to prevent further rotation of said ram; a manually actuated member for withdrawing 90 said key from said slot; and a spring in the same plane with the key for forcing said key 95 inwardly when said member is released.

12. In a self-lowering lifting jack provided with a steep pitch screw, a supporting 100 casing and a vertically movable ram in said casing freely movable lengthwise of the screw when the screw is at rest, said ram having a flat-sided vertical slot extending lengthwise of its periphery; a flat-sided key 105 positioned in an opening in said casing and adapted to partially enter said slot to prevent further rotation of said ram; said key being movable radially to the axis of said screw and in contact with the opposite vertical walls of said opening; a depending manually actuated member for withdrawing said key from said slot, said member being pivoted to said casing near the top of the key; 110 and a spring for forcing said key inwardly 115 against the periphery of the ram when said member is released and impart further inward movement thereto when said slot and key are in the same plane.

Signed at Harvey, Ill., this 1st day of 120 February, 1926.

FRANK L. GORMLEY.
